United States Patent Office

Des. 191,019
Patented Aug. 1, 1961

191,019

AIRPLANE

Armand Jean Thieblot, Hagerstown, Md., assignor to
Fairchild Engine and Airplane Corporation, a corpo-
ration of Maryland

Filed June 10, 1960, Ser. No. 60,915

Term of patent 14 years

(Cl. D71—1)

FIG. 1

FIG. 2

FIG. 3

FIG. 4

FIG. 1 is a top plan view of an airplane, showing the new design;

FIG. 2 is a front elevational view;

FIG. 3 is a side elevational view; and

FIG. 4 is a rear view.

The side of the airplane opposite that shown in FIGURE 3 is substantially the same as the side shown, except for the cabin entrance door as indicated in FIGURE 1.

I claim:

The ornamental design for an airplane, as shown and described.
